(57) **CLAIM**

The ornamental design for a dual screen communication device, as shown and described.

DESCRIPTION

FIG. 1 is a front right side perspective view of the dual screen communication device.

FIG. 2 is a bottom rear perspective view of the dual screen communication device.

FIG. 3 is a front elevation view of the dual screen communication device.

FIG. 4 is a rear elevation view of the dual screen communication device.

FIG. 5 is a top plan view of the dual screen communication device.

FIG. 6 is a bottom plan view of the dual screen communication device.

FIG. 7 is a left elevation view of the dual screen communication device.

FIG. 8 is a right side view of the dual screen communication device.

FIG. 9 is a front elevation view of the dual screen communication device in use displaying coded messages being communicated.

FIG. 10 is a rear elevation view of the dual screen communication device in use; and,

FIG. 11 is a top front left side perspective view of the dual screen communication device within a holder.

The broken lines showing displayed information in FIGS. 9 and 10 and the broken lines showing a holder in FIG. 11 are directed to environment and are for illustrative purposes only; the broken lines form no part of the claimed design.

1 Claim, 6 Drawing Sheets
